UNITED STATES PATENT OFFICE.

WILLIAM HADFIELD BOWERS, OF MANCHESTER, ENGLAND.

RETORT FOR CARBONIZING WOOD.

SPECIFICATION forming part of Letters Patent No. 634,161, dated October 3, 1899.

Application filed December 8, 1897. Serial No. 661,126. (No model.)

To all whom it may concern:

Be it known that I, WILLIAM HADFIELD BOWERS, a subject of the Queen of Great Britain, residing at West Gorton, Manchester, 5 in the county of Lancaster, England, have invented certain new and useful improvements in retorts for the carbonization of wood and other vegetable substances and the drying of manures, sewage, sludge, peat, and 10 other substances and products, (for which I have obtained a patent in Great Britain, No. 17,623, bearing date October 15, 1891,) of which the following is a specification.

My invention relates to improvements in 15 retorts for the carbonization of wood and other vegetable substances and the drying of sewage and manures in large or small quantities, sludge-cake, (which is the residuum left on the top of the filter-bed when the sewage is filtered,) peat, and substances and products 20 generally whether in their natural state or when reduced by any ordinary method of condensation into a form convenient for being subjected to the action of the retort.

According to the said invention the retort 25 is constructed with two or more parallel flues extending in a longitudinal direction along and within the retort and lying one above the other, but both or all, as the case may be, fed 30 by the same furnace and finally discharging into the same outlet. For the purposes of more particular explanation I assume that the retort is constructed with two such flues; but it will be understood that the number of 35 flues may be increased to any number that can be reached by the heat from the furnace. The space immediately over each flue forms a chamber through which an endless chain with bars at suitable intervals and of such 40 width as to sweep the floor or lower surface of the chamber and carried upon sprocket-wheels draws the substance or product to be operated upon (and which I hereinafter refer to as the "material") from the point where 45 it is supplied to the retort along and over the upper flue to the extremity of that flue, where the material falls into a space between such extremity and the sprocket-wheel onto the chain as it runs below. The material is then 50 drawn by the chain in the reverse direction along and over the lower flue until it falls over the extremity of that flue through any

convenient aperture provided for its discharge from the retort. The connection of the lower flue with the higher flue is effected 55 by means of an elbow or outside flue at the point most distant from the furnace. The sprocket-wheels are placed in the same plane with and outside each end of the upper flue at distances convenient for the proper working of the chain and the fall of the material when it reaches the extremity of the upper flue.

The gas driven off during the process escapes by ordinary condenser-pipes, leaving 65 the gas from each chamber to be dealt with in the ordinary manner.

By means of the foregoing arrangement the heat from a single furnace is utilized to heat both the chambers, and the material as it is 70 drawn through the lower chamber is exposed to heat coming from above as well as from below, with the result that labor and time as well as fuel are economized.

The hopper by which the material is fed to 75 the retort is constructed with a bottom hinged at the side farthest from the direction in which the chain travels, so as to fall downward and onto the chain. As the bars of the chain successively catch the lower edge of the hinged 80 bottom they push the bottom onward and upward and close it wholly or in part, and as each bar passes clear from under the edge the bottom falls back, and so releases from the hopper a supply of material which falls 85 onto the chain. The further passage of the material is regulated by means of a check or regulator consisting of a metal plate placed in and extending at right angles across the upper chamber or near a point immediately 90 beyond the space beneath the hopper, but opposite to the side to which the bottom is hinged. This plate hangs and works upon a rod which may or may not project through one or both of the sides of the retort and to which 95 may be fitted a lever by means whereof the plate is raised or lowered as required to permit or regulate the passage of the material. If desired, the resistance of the plate may be automatically regulated by a weight upon the 100 lever. The material is carried through and along each chamber by means of the successive bars of the chain.

In order that my invention may be more

clearly understood, I will now describe, by reference to the accompanying drawings, a mode or manner of carrying the same into practical effect, taking as an example a retort constructed with two flues and two chambers only. It is to be understood that, as before stated, a greater number of flues and chambers may be employed and that the hopper and regulator, as described, may be used for feeding any retort worked with an endless chain passing longitudinally along the heating chamber or chambers.

Figure 1 represents the elevation of a retort constructed according to my said invention. Fig. 2 is a sectional elevation of such a retort. Fig. 3 is a plan showing the positions of the hopper, regulator with lever, and the endless chain and sprocket-wheels.

Similar letters refer to similar parts throughout the several views.

Referring to Fig. 2, the heat passes from the furnace at the point A into and through the lower flue in the direction indicated in the drawings to the farther end of that flue, whence it is carried by an elbow or outside flue A' into the upper flue, and so in the direction indicated to the point N, whence it is discharged into the outer air.

The material being placed in the hopper C is allowed by the hinged bottom e to fall upon the endless chain, the bars G G of which alternately raise and lower the hopper-bottom e, thereby closing the hopper wholly or partly and effecting an intermittent feed of the material upon the chain G G in regular quantities, the material being then carried and swept by the chain against and past the regulator H, which spreads the same evenly across the surface of the chain. The regulator H, which forms an extension of one side of the hopper C and is pivoted to the sides of the drying-chamber, rises slightly while the material is passed underneath it by the chain and is caused to retain its perpendicular position through its own weight or by means of the lever K, acting, if necessary, by means of the weight L. The material is then carried or swept by the bars of the chain through the upper chamber and at the back end of the latter falls between the outer extremity of the flue N and the adjacent sprocket-wheel O onto the chain as it enters the lower chamber P, and so is carried or swept in the reverse direction through the lower chamber 55 and between the upper flue and the lower

flue to the point Q at the extremity of the lower chamber, where it falls or is carried through a convenient aperture into a receptacle or is otherwise discharged from the retort.

The gases evolved during the process are carried off by means of condensing-pipes R and R', fitted at convenient points.

The retort is set and heated and the sprocket-wheels are driven in the ordinary manner.

I prefer to use the endless chain constructed as described; but any equivalent mechanical arrangement for carrying the material along the chambers may be adopted.

What I claim as my invention, and desire to secure by Letters Patent, is—

1. In retorts for carbonizing materials, a single endless bar-chain, running in a horizontal plane, a hot-air flue below the lower portion of the chain, a hot-air flue in the space between the upper and lower portions of the chain, a connection between the lower flue and the intermediate flue consisting of an outside elbow and an exhaust-pipe, connected with the spaces in which the chain travels.

2. In retorts for carbonizing and drying vegetable and other material, a single endless bar-chain rotated by two sprocket-wheels in a horizontal plane inside a chamber and a hopper for feeding the said chain with the material to be treated, the said hopper being furnished with a hinged bottom, adapted to ride upon and be raised and lowered alternately by the chain-bars, all substantially as and for the purpose set forth.

3. In a retort for carbonizing and drying vegetable and other material, a single endless bar-chain rotated by two sprocket-wheels in a horizontal plane inside a chamber, a hopper for feeding the said chain with the material to be treated, furnished at one side with a hinged bottom adapted to ride upon the said chain and on the other side with a pivoted regulator forming an extension and operated upon by the material fed upon the said chain, all substantially as and for the purpose set forth.

In witness whereof I have hereunto set my hand in presence of two witnesses.

WILLIAM HADFIELD BOWERS.
